POWER DRIVE FOR SYRINGES

Filed March 26, 1928

INVENTOR,
Samuel Feinstein
BY
Warren E. Willis.
ATTORNEY

UNITED STATES PATENT OFFICE

SAMUEL FEINSTEIN, OF NEW YORK, N. Y.

POWER DRIVE FOR SYRINGES

Application filed March 26, 1928. Serial No. 264,782.

This invention relates to syringes and more particularly to such as are designed to inject steadily and positively a definite quantity of matter, for instance types known as hypodermic.

In the manipulation of this type of syringe great care must be exercised to hold the syringe firmly and steadily in order to avoid breaking the fine hollow needle through which

10 the liquid matter is dispensed.

It is also important that the quantity of matter be closely regulated in accordance with demand.

As such syringes are ordinarily held and 15 actuated by one and the same hand of an operator, often under difficult conditions and frequently upon nervous subjects shrinking with fear and pain, it is indeed a difficult operation to satisfactorily perform.

20 Not only must the instrument be firmly grasped in order to properly guide the needle and maintain it when in operative position, but considerable energy must be used to force the liquid outwardly through the needle into 25 the living tissue.

It is therefore one of the objects of the present invention to provide a syringe adapted to be securely held and maneuvered in one hand in an effective manner and provided with means for positively advancing 30 its piston or plunger as may be desired without effort on part of the operator.

A further feature is in the provision of a piston operating device mechanically driven 35 and equally applicable to all types of syringes in which pistons are used.

These and other allied objects, such as ease of application, complete control, economy and safety in operation, are attained by the 40 advantageous and novel design, construction and combination of few and simple parts, as hereinafter described and illustrated in the accompanying drawings, forming a material 45 part of this disclosure, and in which:—

Figure 1 is a partial side elevational, partial longitudinal sectional view of a hypodermic syringe made in accordance with the invention.

50 Figure 2 is a similar view taken at a right

angle to Figure 1 but showing a modified form of discharge nozzle.

Figure 3 is a transverse sectional view showing a modification in construction.

The body of the syringe consists of a tube, 55 designated by the numeral 10, the tube having in one side a longitudinal slot 11 and, as shown in Figure 1, is screw threaded at its lower end to receive an inverted cap 12.

Extending outwardly from the cap is a 60 threaded stem 13 having a globular seat at its end and engaged by the stem is a clamp nut 14 having a similar seat to engage a ball 15 carried by a hollow needle 16 passing axially through the nut and stem.

The upper end of the needle passes through a rubber plug 17 forming a closure for the lower end of a glass tube 18 acting as a container for the liquid 19 to be injected, the tube being housed in the casing body 10 and extending past the upper end of its slot 11.

Rigidly fixed on the upper portion of the casing tube 10 is a bracket 20, here shown as a sheet metal loop having extending parallel ends raised at their extremities to provide 75 bearings 21 in which is journalled a spindle 22.

The spindle is preferably driven by a flexible shaft 23, its other end engaging with any convenient rotary driver, such for instance as 80 a hand piece 24, driven by a dental engine.

Fixed on the spindle 22 is a worm 25 meshing with a worm wheel 26 disposed at the end of the body casing 10 and having a hub 27 revolvably fitting within the same.

The worm wheel is provided with an internal thread to engage a screw 28 having a piston 29 at its inner end by which an expandable washer 30 is pressed against the liquid 19, forcing it through the needle.

At the outer end of the screw is a hand knob 31 and at each end of the screw are reduced portions 32—33 to prevent its over actuation as will be understood.

A key way 34 extends longitudinally 95 throughout the length of the screw and engaged therein is a key-like tong 35 formed on the end of a retaining clip 36 secured on the outer side of the bracket 20, opposite its extending arms, this clip holding the worm 100

wheel securely in position on the end of the syringe.

It is apparent that a power drive is widely applicable to different types of syringes in which a piston is used and without respect to the other features of the syringe.

In Figure 3 is shown a modified form of worm gear in which a plain axial opening extends through the hub of a diameter to 10 clear the screw 28.

A pair of flat arms 40 are pivoted at 41 on the outer side of a worm wheel 26', these arms being arranged in opposed relation, their free outer portions being pressed inwardly 15 towards each other by a compression spring 42.

The arms are provided with inreaching threaded elements 43 engageable with the screw 28 to act as a nut in moving it endwise 20 when rotated by the worm.

The elements 43 may be disengaged from the screw by rotating a handle 44 set in the wheel, the handle actuating a cam 45 adapted to separate the arms 40, against the effect of 25 the spring 42, thereby releasing the screw, which may be drawn outwardly through the wheel by the knob 31, thus providing a rapid retraction of the piston.

Obviously, in the simple form shown in 30 Figure 1, the piston is retracted by reversing the direction of rotation of the shaft 23, but it will be understood that any of the common release means may be applied thereto.

Although the preferred embodiment of 35 this invention has been explained in detail, it is understood that minor changes in construction may be made without departing from the spirit and scope of the appended claims.

40 Having thus described my invention, what I claim as new and desire to secure by Letters Patent, is:—

1. The combination with a syringe having a piston movable therein, of a screw stem on 45 said piston, a worm wheel having an internal thread engaged on said stem, means for holding said wheel in operative position on the body of said syringe, means to prevent turning of said screw, said screw having reduced end portions limiting the operation of 50 said wheel, a worm engaging the wheel, and power driven means to actuate said worm.

2. The combination with a syringe having a piston movable therein, of a screw stem on 55 said piston, said stem being reduced in diameter at the ends of its screw threaded portion, means to prevent rotation of said stem, a wheel revoluble on the threaded portion of said stem, power means to rotate said wheel, 60 and means carried by said wheel to engage and disengage the threads on said stem whereby to propel said piston.

3. The combination with a syringe having a piston movable therein, of a screw stem on 65 said piston, said stem being reduced in di-

ameter at the ends of its screw threaded portion, means to prevent rotation of said stem, a wheel revoluble on the threaded portion of said stem, power means to rotate said wheel, a pair of half nuts pivoted on said wheel to engage the threads on said stem, a spring urging said nuts into engagement with said stem, and a manually operable cam for disengaging said nuts.

In testimony whereof I affix my signature. 75

SAMUEL FEINSTEIN.
